SPINDLE DOFFER GUARD

Emile H. Erhard, Dedham, Mass., assignor to
Draper Corporation, Hopedale, Mass., a cor-
poration of Maine

Application September 29, 1934, Serial No. 746,197

5 Claims. (Cl. 118—65)

The present invention pertains to spinning spindles of the type wherein a spindle blade is revolvably mounted in a bearing in a fixed base, and more particularly relates to means for detachably securing the spindle blade in the base against accidental displacement. Such means is known in the art as a doffer guard.

Of the prior doffer guards, the sleeve type, having a projection to overlie a flange on the whorl, is possessed of a number of advantages. It is particularly noted that such sleeves may be substantially devoid of projections which would accumulate lint and dirt and seriously hamper the cleaning of the spindles. However, such doffer guards as previously constructed were so insecure that they would loosen from vibration of the frame and accordingly they have not been used, at least to any appreciable extent.

Accordingly, it is an object of my invention to provide in a doffer guard of the sleeve type means for positively holding the sleeve in position, which means shall be so constructed as to not interfere with the rapid removal of the sleeve when it is desired to remove the spindle.

Further objects will be hereinafter more specifically enumerated, or will become apparent as the description proceeds.

In the specific embodiment of my invention herein disclosed, the spindle base is provided with an annular oil reservoir having a cylindrical wall. The sleeve fits over this wall and is provided with an inwardly projecting portion which overlies a flange on the whorl. A bayonet-type connection detachably secures the sleeve to the base, the pin of this connection being in the sleeve and the slot thereof being the base. A second pin is slidable in the sleeve in position to engage in the slot when the sleeve is turned to locking position. This second pin positively prevents accidental turning of the sleeve to unlocked position, but is so readily manipulated that it does not appreciably interfere with the intentional removal of the sleeve.

The said specific embodiment, which is at present preferred, is illustrated on the accompanying drawing, of which:

Fig. 1 is a view in elevation of the complete spindle;

Fig. 2 is a view similar to Fig. 1 but with the lower part of the spindle sectioned as indicated by line 2—2, Fig. 1;

Fig. 3 is a fragmentary elevational view of the spindle with the doffer guard sleeve removed; and

Fig. 4 is a perspective view of the sleeve detached from the spindle.

The spindle shown on the drawing is comprised of a spindle blade 1 having a whorl 2 fixed thereto, a base 3 fixed to the spindle rail R as by a nut 4, and a suitable bearing such as bolster 5 in which the spindle blade revolves.

The base includes a flange 6 and cylindrical wall 7 which constitute an oil reservoir. Oil feeds from the reservoir through leads 8 into the interior of the tubular portion 9, from whence it feeds through leads in the bolster to the spindle blade. The oil feeds up the spindle blade, over the top of the base and downwardly along the cylindrical surface 10 on the interior of the 15 whorl, from whence it is thrown by centrifugal force against the frusto-conical surface of oil-collecting member 11.

The oil-collecting member receives the oil and returns it to the interior of the oil reservoir. The 20 upper edge of this member terminates within a groove 12 formed in the lower face of the whorl. The member 11, as well as the other parts of the spindle thus far described in detail are conveniently the same as in my co-pending application 25 Serial Number 746,198, filed of even date here-with.

The external surface of the wall 7 is preferably cylindrical except for a bayonet slot therein. This slot is comprised of a vertical portion 13 30 which extends downwardly from the top of the wall 7, and a circumferentially extending portion 14 which communicates with and is angularly related to the portion 13. A cylindrical sleeve 15 fits over the wall 7, with a sliding fit. A projection, as pin 16 in the sleeve cooperates with the slot, thereby forming a bayonet-type connection between the sleeve and the base.

The lower edge of the whorl is provided with an outwardly projecting annular flange 17, and 40 an inwardly projecting portion on the sleeve 15 overlies this flange, whereby the sleeve serves as a readily removable doffer guard. Preferably, the said portion of the sleeve is constituted by inwardly turned rim 18.

My invention provides readily releasable means for positively locking the sleeve against accidental rotation. Such means in the present embodiment is constituted by a headed pin 19 which has a reduced portion intermediate its ends 50 engaged in a vertical slot 20 in the sleeve. The pin may slide quite freely in its slot, and is so located that when the sleeve is in locked position (the pin 16 being then at the closed end of slot 14) the pin 19 drops down into the slot 13. Thus, 55

the sleeve cannot be rotated until the pin 19 is manually raised out of the slot 13. This last operation may be performed practically simultaneously with the rotation and removal of the sleeve, and thus it performs its functions without materially adding to the time required to remove the spindle blade from the base.

An advantage of the specific embodiment shown is that the pin 19 will assume its locking position automatically. That is, when the sleeve is slid down onto the base and rotated to the position of Fig. 1, the pin 19 will move downwardly into the slot 13 by gravity.

Having fully disclosed the preferred embodiment of my invention, I claim:

1. A spinning spindle comprised of a spindle blade having a whorl fixed thereto, a base having a cylindrical surface co-axial with said blade, a flange on said whorl, a sleeve fitting over said cylindrical surface and having a portion overlying said flange, a bayonet-type connection between said sleeve and said base, and manually releasable means for locking said sleeve against rotation in either direction.
2. A spinning spindle comprised of a spindle blade having a whorl thereon, a base within which said spindle revolves, a sleeve rotatably and detachably mounted on said base, said spindle extending through said sleeve, a flange on the lower edge of said whorl, doffer guard means on said sleeve overlying said flange, and a manually operable pin mounted in said sleeve for sliding movements to and from a position where it locks said sleeve to said base.
3. A spinning spindle comprised of a spindle

blade having a whorl thereon, a base within which said spindle revolves, a sleeve rotatably and detachably mounted on said base, said spindle extending through said sleeve, a bayonet-type connection between said sleeve and base, a flange on the lower edge of said whorl, a portion on said sleeve overlying said flange, and a pin carried by said sleeve and slidably axially thereof for engaging said base and thereby releasably locking said sleeve against rotation.

4. A spinning spindle comprised of a spindle blade, a whorl, a base having a cylindrical external surface, there being communicating circumferential and axially extending slots in said surface, a flange on said whorl, a detachable sleeve rotatably fitting over said surface, said sleeve having a portion overlying said flange, a projection on said sleeve engaging in said circumferential slot, and a pin slidably mounted in the sleeve for engaging said axially extending slot to thereby releasably lock said sleeve against rotation.

5. A spinning spindle comprised of a spindle blade, a whorl, a base having a cylindrical external surface, a flange on said whorl, a sleeve rotatably fitted over said surface, said sleeve having a doffer guard portion overlying said flange, a bayonet-type connection between said sleeve and said base, and manually releasable means, in addition to said connection, for automatically locking said sleeve against rotation in either direction, said means being operable by gravity upon rotation of the sleeve to a predetermined position.
